UNITED STATES PATENT OFFICE

2,463,161

COIN SEPARATOR

Francis C. Du Grenier, Haverhill, and Frank B. Perri, Groveland, Mass.; said Perri assignor to Blanche E. Bouchard, Haverhill, Mass.

Application September 22, 1945, Serial No. 617,990

9 Claims. (Cl. 133—3)

1

This invention relates to coin separators or classifiers, as commonly used on coin-operated vending machines of all sorts, and particularly for machines vending articles of different value for coins of different value.

It has been the customary practice in such machines heretofore to provide separate coin openings or slots, and coin chutes for each value of coin used. This has caused unnecessary complexity and expense making such machines and unnecessary difficulty in operating them, particularly because of the careless operator who is unable to always get the proper coin in the proper slot. In such case the coin is returned to the operator, who then may report the machine as out of order, requiring unnecessary inspection, or servicing, or he may seek to make the machine work or damage it by the application of unnecessary or improper force. In line with the effort to make coin-operated machines as foolproof as possible, we have devised mechanism which permits one coin opening to be used for all values of coins, and which separates each coin according to its value, and directs it into its proper coin-chute for subsequent testing and use in operating the machine.

In operation, this mechanism separates coins according to their size or diameter, the largest coin being first separated out, then the next largest, and so on until all sizes have been disposed of. For purposes of illustration, the device is shown as used with quarters, nickels and dimes, but it is to be understood that the device may be used with half dollars or pennies also, as well as the coins of foreign countries.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Further objects and advantages will appear in the following specification, in connection with the accompanying drawings, in which

Fig. 1 is a fragmentary view, in elevation, of coin separating mechanism embodying the invention;

Fig. 2 is a plan view thereof;

Fig. 3 is a rear view; and

2

Fig. 4 is a vertical section taken on the line 4—4 of Fig. 1.

In the drawings, 10 represents a back plate or rear wall-forming element (which may be the side casing of the vending machine) and mounted over it but spaced apart from it by suitable steps 11 and attached thereto as by screws 12 is front plate 14 forming the front wall for the coin-separating mechanism. A coin opening or slot 15 is provided which leads into the coin chute 16 formed by suitable flanges or sides 17 preferably formed or mounted on back plate 10, in any suitable manner, as by welding, coin slot 15 and chute 16 being large enough to receive all coins with which the mechanism is to operate. Coin chute 16 preferably slopes downwardly and its angle of inclination and its length is determined by the weight of the various coins to be used, so that each coin may acquire sufficient momentum on being inserted into coin slot 15, to operate the coin-separating devices 20 hereafter described. Each coin separator 20 differs in size, weight and proportions according to the coin it is designed to separate out, and comprises a 25 tiltable member suspended for oscillating or swinging movement outwardly and inwardly on an axis parallel to the bottom wall 17 of coin chute 16. For this purpose each separator 20 has a short shaft 22 extending perpendicularly through it at its top shank 21 which constitutes its axis of oscillation, in which it is pivotally mounted in bearings 23 preferably provided on the back of back plate 10 by an adjustable bracket 24. Top shank 21 of each separator 20 then extends forwardly beyond coin chute 16 and then turns to the left into side shank 25 which extends parallel to coin chute 16 for a distance approximately equal to the length of top shank 21, and then turns downwardly into down shank 26 for a distance slightly less than the diameter of the coin the separator 20 is designed to separate out, and then carries on its bottom end a shelf 27 which extends inwardly into coin chute 16 and forms the bottom wall 17 thereof for the extent of the length of shelf 27. By this arrangement it will be seen that shelf 27 is offset or spaced downwardly of the coin chute 16 and in staggered relation from the top shank 21. It will be understood that suitable apertures are 35 cut into front plate 14 to provide space for each separator 20 to extend over and through plate 14 into coin chute 16. In the particular embodiment of the invention herein shown, the first coin separator 20A on coin chute 16 is designed to 40 separate out quarters (25¢) and the distance 45

between the bottom side of top shank 21 and bottom wall 17 of coin chute 16 and shelf 27 is consequently somewhat less than the diameter of a quarter. In addition the weight and balance of coin separator 20A is so adjusted and proportioned that the momentum of a quarter passing down coin chute 16 will cause the quarter to first strike the bottom edge of top shank 21 and thus lift or tilt separator 20A, so that its shelf 27 will be lifted out of alignment with the bottom wall 17 of chute 16 and thus permit the quarter to drop into quarter chute 30, where it is tested by several coin detecting devices, and, if passed, is carried into the coin-controlled mechanism of the vending machine. It will be understood that quarter chute 30 is formed by a suitable flange 31 welded or soldered to back plate 10.

The second or nickel separator 20B is similar in all respects to the first coin separator 20A, except that it is smaller in size, and is so adjusted and proportioned in weight and balance that the momentum of a nickel passing down coin chute 16 will cause the nickel to strike the bottom edge of top shank 21, tilting separator 20B, and thus lift its shelf 27 out of alignment with the bottom wall 17 of chute 16, and thus permit the nickel to drop into nickel chute 32, where it will be tested by coin-detecting devices and thence be carried into the coin-controlled mechanism of the machine. In this instance nickel chute 32 preferably passes through and behind back plate 10 through a suitable aperture 33 provided therein.

Having separated out quarters and nickels, only dimes are left to pass into dime chute 34, formed by a flange 35 on back plate 10 and no separator for dimes is necessary. It will be understood that the usual coin-detecting devices are also provided for the dimes, and pennies or slugs will be rejected thereby.

In operation, of course, dimes will by-pass both coin-separators 20A and B, and nickels will by-pass the quarter separator 20A. It will be seen, therefore, that the coin separators acting on the diameter of the coin, rather than its weight or other characteristic thus provide a simple, accurate, and rugged means of separating coins for coin-operated machines vending articles of different value for coins of different value.

We claim:

1. A coin separating mechanism, including an inclined chute down which coins of different value and diameter are adapted to roll, a tiltable member pivoted on an axis parallel to the bottom wall of said chute, said axis extending longitudinally of said chute having an arm extending over the top of said coin chute and in the path of a rolling coin therein, and carrying on its lower end a shelf in staggered relation from said arm and forming a removable part of the bottom wall of said chute and adapted to be tilted by coins of one diameter to cause such coins to pass into a separate chute, and to pass all coins of smaller diameter into another chute.

2. A coin separating mechanism, including an inclined chute down which coins of different value and diameter are adapted to roll, a plurality of tilttable members successively disposed along said chute pivoted on an axis parallel to the bottom wall of said chute, said axis extending longitudinally of said chute and each having an arm extending over the top of said coin chute and in the path of a rolling coin therein and carrying on its lower end a shelf in staggered relation from said arm and forming a removable

part of the bottom wall of said chute, each member being adapted to be tilted by a coin of different and successively diminishing diameter to cause coins of different diameter to pass into separate chutes.

3. A coin separating mechanism, including an inclined chute down which coins of different value and diameter are adapted to roll, a tilttable member having an arm extending over the top of said coin chute and in the path of a rolling coin therein and carrying on its lower end a shelf in staggered relation from said arm and forming a removable part of the bottom wall of said chute, the distance between the underside of said arm which extends over the top of said chute and the bottom wall of said chute being slightly less than the diameter of the coin it is designed to separate, whereby said member will be tilted by coins of said diameter to cause such coins to pass into a separate chute, and to pass all coins of smaller diameter into another chute.

4. A coin separating mechanism, including an inclined chute down which coins of different value and diameter are adapted to roll, a plurality of tilttable members successively disposed along said chute pivoted on an axis parallel to the bottom wall of said chute, said axis extending longitudinally of said chute and each having an arm extending over the top of said coin chute and in the path of a rolling coin therein and carrying on its lower end a shelf in staggered relation from said arm and forming a removable part of the bottom wall of said chute, the distance between the underside of said arm which extends over the top of said chute and the bottom wall of said chute being slightly less than the diameter of the coin it is designed to separate, said members being adapted to be tilted by coins of successively diminishing diameter, whereby coins of different diameters are caused to pass into separate chutes.

5. A coin separating mechanism, including an inclined chute down which coins of different value and diameter are adapted to roll, a tilttable member pivoted on an axis parallel to the bottom wall of said chute, said axis extending longitudinally of said chute, and having an arm extending over the top of said coin chute and in the path of a rolling coin therein and carrying on its lower end a shelf spaced downwardly of said coin chute in staggered relation from said arm forming a removable part of the bottom wall of said chute, and adapted to be tilted by coins of one diameter to cause such such coins to pass into a separate chute, and to pass all coins of smaller diameter into another chute.

6. A coin separating mechanism, including an inclined chute down which coins of different value and diameter are adapted to roll, a plurality of tilttable members successively disposed along said chute, each pivoted on an axis parallel to the bottom wall of said chute, said axis extending longitudinally of said chute and each having an arm extending over the top of said coin chute and in the path of a rolling coin therein and carrying on its lower end a shelf spaced downwardly of said coin chute in staggered relation from said arm, and forming a removable part of the bottom wall of said chute, each member being adapted to be tilted by a coin of different and successively diminishing diameter to cause coins of different diameters to pass into separate chutes.

7. A coin separating mechanism, including an

inclined chute down which coins of different value and diameter are adapted to roll, a tilttable member pivoted on an axis parallel to the bottom wall of said chute, having an arm extending into the top of said coin chute and in the path of a rolling coin therein, and carrying on its lower end a shelf spaced downwardly of said coin chute in staggered relation from said arm and forming a removable part of the bottom wall of said chute, the distance between the underside of said arm which extends into the top of said chute and the bottom wall of said chute being slightly less than the diameter of the coin it is designed to separate, whereby said member will be tilted by coins of said diameter to cause such coins to pass into a separate chute, and to pass all coins of smaller diameter into another chute.

8. A coin separating mechanism, including an inclined chute down which coins of different value and diameter are adapted to roll, a tilttable member pivoted on an axis parallel to the bottom wall of said chute, said axis extending longitudinally of said chute, and having an arm extending into the top of said coin chute and in the path of a rolling coin therein, and carrying on the downward end of said arm a downwardly extending shank, in turn carrying on its lower end a shelf spaced in staggered relation from said arm and forming a removable part of the bottom wall of said chute, and adapted to be tilted by coins of one diameter to cause such coins to

pass into a separate chute, and to pass all coins of smaller diameter into another chute.

9. A coin separating mechanism, including an inclined chute down which coins of different value and diameter are adapted to roll, a tilttable member pivoted on an axis parallel to the bottom wall of said chute having an arm extending into the top of said coin chute and in the path of a rolling coin therein, and carrying on the downward end of said arm a downwardly extending shank in turn carried on its lower end a shelf spaced in staggered relation from said arm and forming a removable part of the bottom wall of said chute, the distance between the underside of said arm which extends into the top of said chute and the bottom wall of said chute being slightly less than the diameter of the coin it is designed to separate, whereby said member will be tilted by coins of said diameter to cause such coins to pass into a separate chute, and to pass all coins of smaller diameter into another chute.
